US0D1087705S

(12) **United States Design Patent** (10) **Patent No.:** **US D1,087,705 S**
(45) **Date of Patent:** **** Aug. 12, 2025**

(54) **FOOD CONTAINER**

(71) Applicant: **Meng Wu**, Guangdong (CN)

(72) Inventor: **Meng Wu**, Guangdong (CN)

(**) Term: **15 Years**

(21) Appl. No.: **29/987,331**

(22) Filed: **Jan. 23, 2025**

(51) **LOC (15) Cl.** **09-07**

(52) **U.S. Cl.**

USPC **D7/629**

(58) **Field of Classification Search**

USPC ..... D7/351, 637, 709, 600.2, 600.1, 600.3, D7/600.4, 590, 629, 405, 641, 612, 392.1, D7/391, 610; D3/295, 313; D9/503, 761 CPC G01D 7/04; G01R 13/02; G05D 23/1913; F24C 7/06; A47B 88/994; A47B 88/90; A47B 2210/07; B65D 21/086; B65D 1/36; B65D 81/2038; B65D 43/0218; B65D 43/0225; B65D 43/0214; B65D 45/20; A45C 11/20; A47K 10/421; A47J 31/44; A47J 47/16; A47J 47/01; A47G 23/025; A47G 19/18; A47G 19/26; A47G 19/30; G01F 11/023; G01F 11/028; B05B 11/0086; B05B 11/1042; B05B 11/1011

(57) **CLAIM**

The ornamental design for a food container, as shown and described.

DESCRIPTION

FIG. 1 is a front, right and top perspective view of a food container, showing my new design;

FIG. 2 is a rear, left and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is a front, right and bottom perspective view of the food container, shown in an alternate configuration.

The broken lines in the drawings depict portions of the food container that form no part of the claimed design.
